UNITED STATES PATENT OFFICE.

RICHARD H. SMITH, OF NORTON, MASSACHUSETTS, ASSIGNOR OF ONE-THIRD TO HOMER L. LANE AND ONE-THIRD TO CHARLES H. LANE, BOTH OF NORTON, MASSACHUSETTS.

VALVE-OPERATING MECHANISM.

Application filed April 17, 1923. Serial No. 632,694.

To all whom it may concern:

Be it known that I, RICHARD H. SMITH, a citizen of the United States, residing at Norton, in the county of Bristol and State 5 of Massachusetts, have invented certain new and useful Improvements in Valve-Operating Mechanism, of which the following is a specification.

My invention relates to a device for 10 manually operating globe valves, angle valves, gate valves, and such other types of valves as embody a slidable valve stem.

The essential objects of my invention are 15 speed in opening and closing the valve; prevention of accidental unseating of the valve even under a maximum pressure; to adapt the device for application to a valve casing located adjacent an obstacle, and enable its operation under such circumstances; to facilitate the interengagement 20 of the valve bonnet or head with the shell of the casing when such portions of the shell are separate and threaded; certainty of action, strength; and simplicity. Other 25 objects and advantages of the invention will be apparent as it is better understood from the following description and accompanying drawings.

To the above ends essentially my invention 30 consists in such parts and in such combinations of parts as fall within the scope of the appended claims.

In the accompanying drawings forming 35 a part of this specification, illustrating the principle of this invention, and the best mode now known to me of applying this principle,

Figure 1 is a plan of my device applied 40 to a globe valve,

Figures 2 and 3, fragmentary side elevations of the same showing the parts in closed and open positions respectively,

Figure 4, a vertical central section, and

Figure 5, a front elevation of the same 45 showing the parts broken away.

Like reference characters indicate like parts throughout the views.

In the construction illustrated 7 is the shell and 8 the head or bonnet of a globe valve casing 9, provided with the usual partition 10, opening 11, and annular shoulder 12 constituting the valve seat 13. The bonnet or head 8 includes the body 15, sleeve 17, and flange 18 provided with

thread 19 engageable with thread 20 on the 55 shell, all as usually constructed. 22 is the gland in threaded engagement with the portion 17. Slidable in the head is the stem 24 of a valve 25 which in the construction illustrated is a piston. The shape of the 60 member 25 as well as its corresponding seat is immaterial and is dependent obviously upon the type of valve and valve casing.

The valve stem 24 has upon its upper 65 end a thread 28 engaging the internal thread 29 in the central opening 30 of a sleeve 31 constituting the lower portion of a head 32 whose upper portion consists of spaced parallel vertical ears 34 integral with the sleeve or shank 31. Fast in the 70 ears is a pivot pin 36 passing loosely through a hole 37 in a downwardly and rearwardly inclined extension or heel 38 upon the inner end portion 39 of a lever 40 terminating in a handle 41 the heel being 75 disposed at an angle to the lever. The head 32 is fastened in adjusted position by a lock nut 43 on the valve stem.

The sleeve portion of the valve casing 80 head 8 has a transversely rectangular external groove 44 in which is mounted a split clamping ring 45. In this instance the ring comprises two body sections 46 having upon their ends ears 47 provided with threaded perforations 48 to receive clamping 85 screws or bolts 49. By turning the screws the ring may either be made rigid on the head 8 or may be loosened to move circularly thereon. Each ring section 46 has midway its length lateral studs 52 in 90 which are threaded pins or pivot members 53 loose in openings 54 in the lower ends of links 56 having enlarged upper portions 58 provided with bores 60 to receive a shaft 95 or pivot member 61 which also passes through a bore or opening 62 in the broad end portion or sleeve 39 of the arm 40. A cross bar 64 connects the links adjacent the valve stem head 32. The links, cross bar, and shaft 61 constitute a swinging 100 frame 65.

The valve 25 is unseated by slightly elevating the lever 40 which destroys the normal vertically aligned relation of the members 61 and 36, and the upper portion of 105 the frame 65 is thus thrown rearwardly, as shown in Figure 3. A reversal of the lever movement returns the parts to original po-

sition with the cross piece 64 abutting against the head 32, as shown in Figure 4, whereby the pivotal centers 61 and 36 are prevented from moving far from their vertical relation with each other. The toggle or clamping action described enables the application of excessive power to the valve steam in closing, and hastens the opening of the latter.

10 The adjustable character of the ring 45 permits turning the lever 40 in direction laterally, so that my device may be accommodated in otherwise inaccessible locations.

15 Adjustment for wear of the valve is afforded by the threaded engagement of the valve stem 20 in the member 32.

It is to be understood that the invention is not limited to the specific form herein illustrated and described, but may be embodied in other forms without departing 20 from the spirit as defined by the following claims.

I claim:—

25 1. In a valve operating mechanism, a valve casing, a valve stem, a swinging frame pivotally mounted and carrying a cross member joining the sides of the said frame and adapted to engage the stem when the frame is moved in one direction, and a lever 30 of elbow form pivoted at its elbow on the upper end of said frame and connected with the valve stem.

35 2. In a valve operating mechanism, a valve casing, a valve stem, a swinging frame pivotally mounted and carrying a cross member joining the side members of said frame and adapted to engage the stem when the frame is moved in one direction, and a lever 40 of elbow form pivoted at its elbow on the upper end of said frame, and fulcrumed on the said valve stem.

45 3. In a valve operating mechanism, a valve casing, a valve stem, a swinging frame pivotally mounted and carrying a cross member, and a lever of elbow form pivoted at its elbow on the upper end of said frame, and fulcrumed on the said valve stem, said lever being movable to bring the

50 pivot of its elbow upon either side of the vertical axis of the stem.

4. In a valve operating mechanism, a valve casing, a valve stem, a ring on the casing, a vibratory frame attached at its lower end to the ring and movable transversely 55 of the stem, a head on the stem in the path of the frame and adapted to be engaged thereby, a lever pivotally attached to the upper end of the frame for vibrating the frame, and a heel upon the lever pivotally supported by the head the pivot of the upper end of the frame and the pivot of the head being relatively movable to and from 60 normal vertically aligned relation.

5. In a valve operating mechanism, a valve casing, a valve stem, a head on the stem, a ring on the casing concentric with the stem, a frame comprising links pivotally attached at their lower ends to the ring at diametrically opposite points, a cross piece connecting the links adjacent the 70 head, and a pivot pin in the upper portions of the links at a distance from the cross piece, an operating lever pivoted upon the pin between the links, and a heel on the pivoted end of the lever pivotally engaging 75 the head the pivot of the upper portion of the frame and the pivot of the head being relatively movable to and from normal vertically aligned position.

6. In a valve operating mechanism, a 80 valve casing, a valve stem, said casing being provided with an annular recess concentric with the stem, a split clamping ring comprising a body seated in the recess and ears provided with perforations, clamping screws in the perforations, a frame pivotally attached to the ring, and a lever pivoted to the frame and fulcrumed upon the stem the pivot between the lever and frame and the pivot of the stem being relatively 85 movable to and from normal vertically aligned relation.

In testimony whereof I have affixed my signature.

RICHARD H. SMITH.
